COVER FOR GOLF CLUB CARRYING CASE

John L. Findeisen, 11026 S. Avenue L,
Chicago, Ill. 60617

Filed Oct. 12, 1973, Ser. No. 405,931

Term of patent 14 years

Int. Cl. D21—02

U.S. Cl. D34—5 GB

FIG. 2

FIG. 3

FIG. 1 is a perspective view of a cover for a golf club carrying case illustrating its configuration when in place about a carrier;

FIG. 2 is an extended plan view of the cover shown in FIG. 1;

FIG. 3 is a bottom end view of the cover showing the three dimensional shape assumed by the cover when in place as shown in FIG. 1.

I claim:

The ornamental design for a cover for golf club carrying case, as shown and described.
